UNITED STATES PATENT OFFICE.

THOMAS J. MURDOCK, OF LAWRENCE, MASSACHUSETTS.

BOBBIN AND COP BUILDER FOR YARN-WINDING MACHINES.

SPECIFICATION forming part of Letters Patent No. 393,717, dated November 27, 1888.

Application filed April 16, 1888. Serial No. 270,817. (No model.)

To all whom it may concern:

Be it known that I, THOMAS J. MURDOCK, a citizen of the United States, residing at Lawrence, in the county of Essex and State of Massachusetts, have invented certain new and useful Improvements in Bobbin and Cop Builders for Yarn-Winding Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to bobbin and cop builders for yarn-winding machines, whereby the yarn, passing about a rapidly continuously-revolving spindle or series of spindles set in a frame, is caused to traverse lengthwise of the 20 cops in process of building, the traverses of the yarn constantly varying in length to give the requisite and proper shape to said cop when the latter is filled or completely built.

25 My invention relates to mechanism by which the traverses of the yarn-guide wire to control the lay or wind of the thread are so controlled that my bobbin-winder is equally well adapted to build or fill cops, paper shells, and bobbins formed either with or without a 30 "cone-head," so called. Furthermore, it will wind from bobbins, small or large spools, or from beams—in fact, is suitable to wind any kind of a thread which requires to be transferred or rewound from one article containing 35 it to another. Moreover, by the adjustment of the co-operating component parts, this machine is capable of forming the cone-head of thread, and thus the cone-head upon the bobbin may be dispensed with.

40 My invention consists in certain devices and the construction and combination thereof, as hereinafter more particularly set forth and claimed, having for their purpose the regulation of the position of the thread as it passes 45 about the bobbin, and also the amount of thread laid on any part of said bobbin.

The drawings represent in Figure 1 a side elevation and in Fig. 2 a plan of a machine for building and winding bobbins and embodying my invention. Fig. 3 is an end view of the same, also showing the connection of the faller-

5 arm with the suspensory rod. Fig. 4 is an enlarged side view of the mechanism for operating the feed to produce end traverses of the builder-shoes. Fig. 5 is a modified form of 55 the cam-plate on the rotating wheel oscillating the lever which actuates the faller-arm.

In said drawings, A A represent two similarly-shaped builder-shoes adapted to reciprocate in guides formed in the castings B B, 60 secured to the floor. Said builder-shoes are united by a rod, a, and constructed with lateral walls, the upper edges of which in profile are shaped and sloped to control the vertical drop of the rail C, which rests and is sup- 65 ported at each end by transverse pins b b. This rail is further provided with a similarly-disposed pin, a', which engages in a vertical slot, b', formed in a standard, A', fastened to the floor or otherwise. By this means the rail 70 has no endwise travel, but is permitted to rise and fall dependent upon the builder-shoes. Moreover, said rail is caused to bear firmly upon the builder-shoes by the superincumbent weight of the several component parts, 75 which are mounted upon it.

The main driving shaft is shown at D, upon which are affixed, in the present instance, two sprocket-wheels, E F, which operate, respectively, two sprocket-wheels, G H, by aid of the 80 belts c d; but other means of transmitting motion may be adopted in lieu of the sprocket-wheels herein shown. The wheel H (see Fig. 4) is journaled in a standard, e, laterally of the rail, and is furnished with a projecting stud, 85 f, which engages the free end g of a species of bell-crank lever, I, pivoted in a standard, J. The tail end h of this lever is fitted with an adjustable chain, i, attached to an arm, j, carrying a pawl, which operates a ratchet-wheel, 90 K, rigidly secured upon one end of a screw-threaded shaft, L, mounted in the casting B. The adjustment of chain i is effected by a bolt, i', to which the upper end of the said chain is attached, said bolt being movable backward 95 or forward in a slot, h', of the end h of said lever, and loosened or tightened as occasion may require. The opposite end of said shaft engages one of the builder-shoes, and upon rotation of the main shaft and the interconnect- 100 ing mechanism said builder-shoes are thrust endwise, (see arrow 2,) permitting the rail to

drop, and thus alters the position of the guide-rod P , which moves longitudinally of the bobbin or cop in process of winding.

The adjustment of the connecting chain or link i upon the tail end of the lever produces more or less movement of the pawl on the ratchet-wheel, and the travel of the builder-shoes is thereby increased or diminished within a given unit of time to accommodate varying sizes of yarn or thread in process of winding.

The sprocket-wheel G , before mentioned, is journaled and mounted on the rail C , and is actuated continuously by the belt e to the wheel E on the main shaft. This wheel co-operates with an oscillating lever, M , composed of two parts, l m , adjustably connected by means of a slot, m^2 , in one of said parts, and a bolt, m' , passing through it. The pivotal end of said lever is fixed to the rail by an ear or bracket, while its free end rests upon and is wiped by two anti-friction rollers, n , secured laterally of the wheel G . Said rollers are located diametrically of each other and alternately lift the free end of said faller-arm lever M , which causes the faller-arm N , with which it is movably united, to operate and rock the suspensory rod O and guide-wire P . In lieu of said rollers n n' , a cam-plate, n' , (see Fig. 5,) may be secured to the wheel G , the shape of the cam to be such and to so operate the guide-wire that the thread shall move with a continuously-varying speed lengthwise of the bobbin, the speed of the traverse increasing from the head to the end of the bobbin, while the speed is just the reverse when the downward or retreat traverse is produced. Said upward travel of the guide-wire is created by the spring c' , secured at one end upon the suspensory rod and at the other to the frame in which the bobbins are mounted. Said spring is permitted to move the guide-wire only as the other component operating parts change their relative positions dependent upon the speed of the machine. In the use of a cam-plate the anti-friction roller is then placed in the lever M . (See Fig. 5.)

The faller-arm N is composed of a curved link, p , rigid upon the suspensory rod O , and further pivoted to a straight arm, q , adjustable in length, the said arm q consisting of two sections, one of which has a longitudinal slot, q' , through which bolts q^2 q^2 pass to effect the adjustment. The lower extremity of said faller-arm is movably connected with its oscillating lever M by the anti-friction rollers r r' , which are placed one on each side thereof. Movement of this lever M causes movement of the faller-arm, and rocking motion is imparted thereby to the suspensory rod. Secured at intervals along the latter are set a series of arms, s , which uphold the guide-wire P , by which the thread Z , passing thereunder, is caused to traverse longitudinally along the bobbin in operation. A spindle carrying a bobbin is shown at Q as mounted in a frame of the ordinary construction, and each bobbin is rapidly rotated in the manner now usually prac-

ticed; hence it will be unnecessary to describe or show said actuating mechanism.

The parts above described, the stationary rail adapted to move vertically, induced by the endwise travel of the builder-shoes actuated by their feed mechanism, together with the oscillating faller-arm lever operated by the continuously-rotary wheel G , with its cam-plate p' , serve to produce two results in the act of building a bobbin: First, the fall or vertical drop of the rail by the movement of the builder-shoes serves to change the position of the guide-wire P lengthwise of the bobbin, gradually lifting said wire, and hence serves to change the place where the thread passes about the bobbin at each traverse; secondly, the movement of the cam-plate, which oscillates the faller-arm lever and rocks the faller-arm and suspensory rod, causes the proper length of traverse of the guide-wire along the bobbin. Thus it is manifest that so long as the free end of the faller-arm remains in the same place upon its actuating lever the oscillations of the latter will produce equal traverses of the thread upon the bobbin as the latter revolves; but as the rail drops, owing to the feed movement of the builder-shoes, the guide-wire is moved lengthwise of and upwardly on the bobbin, and the traverses cause the thread to be laid upon said bobbin according as the shape of the latter has been determined, this being uniform and exact for all the bobbins made simultaneously by the machine with a certain adjustment of the parts.

To change the length of the traverses and cause them to automatically vary, as is required to complete the proper shape of the bobbin, I have located at one side of the machine, in proximity to the foot of the faller-arm, a standard, R , with two upright supports, u u , in which is disposed a sliding rod, t , one end of the latter being furnished with a guide-head, S . The lower end of this head terminates in an interiorly-screw-threaded hub, which engages with and is actuated by a horizontal screw-shaft, T , also mounted in said standard R .

Longitudinally of the machine, and secured to one of the builder-shoes, by which endwise movement is imparted to it, is placed a straight bar, V , furnished with a toothed rack, w , engaging a toothed wheel, x , on the inner end of a short shaft, W , mounted in the standard R . The outer extremity of said shaft has a bevel-gear, y , meshing with a pinion, z , upon the screw-shaft T .

Endwise movement of the builder-shoes (see arrow 2) causes the bar V to be advanced with it, and the rack w rotates the toothed wheel x , also the gears y z and the shaft T . Rotation of the latter thrusts the guide-head S against the free end of the faller-arm N , which is retained thereagainst by the spring 3 . The lower free end of the faller-arm is thus impelled in the direction of arrow 3, and is thrust outwardly upon the oscillating lever M ; but since the throw of the latter is the same (un-

less changed by adjustment) at all times during the operation of filling a bobbin or series of bobbins the travel of the faller-arm is increased and its traverse lengthwise of the bobbin is greater. Furthermore, the length of the rack is such that it serves to operate the guide-head and faller-arm until the largest diameter of the bobbin-bottom is obtained, when the rack is disengaged from the toothed wheel 10 by the further advance of the bar V. Said toothed wheel then ceases to operate, the guide-head remains stationary, and the length of the traverses now continues of the same length. When the bobbins are filled, the machine is 15 stopped, the movement of the builder-shoes is reversed, and they are brought into the position shown in Fig. 1. This retreat movement of the builder-shoes again causes the rack to engage its toothed wheel, and all the operating parts are reversely actuated, whereby the 20 guide-head is restored to its first position, (see Fig. 1,) in readiness for the act of refilling empty bobbins. In said drawings, Fig. 1, the bobbin is represented as just starting to be filled, and the guard-wire is at its extreme upward throw, the traverse being very short to build up the cone, say on a paper shell or upon a bobbin formed without a cone-head. The cam or actuating plate on the wheel G now 25 permits the faller-arm lever to drop to its lowest position or extreme downward oscillation.

The spindle-supporting devices hereinbefore described and shown are fixed.

What I desire to claim is—

- 35 1. The combination, with the vertically-movable rail, the spring actuated reciprocating faller-arm, a lever, and movable rail for causing such reciprocation, of the guide-head which engages the free end of the faller-arm, 40 the builder-shoes, and the rack-carrying bar, with its co-operating wheel screw-shaft and intervening gearing, substantially as herein specified.

2. In combination, the builder-shoes A, connecting-rod *a*, sprocket-wheels F H, connecting-band *d*, the bell-crank lever I, operating-pawl *j*, screw-rod L, the chain *i*, ratchet-wheel K, the rail C, movable in vertical planes and mounted upon the builder-shoes, and the guide-wire, the faller-arm, spring *c'*, the suspending devices for said guide-wire, the lever M, pivoted to said rail and movably connected to said faller-arm, the wheel G, carrying cams which act on said faller-arm, and mechanism for rotating said wheel, all operating substantially as described. 45 50 55

3. The combination, with a continuously-rotary spindle, a vertically-movable rail, means for actuating said rail, the oscillating lever and the continuously-rotary wheel carried by the 60 rail, the cam face-plate, and the actuating-wheel E, of the spring-actuated suspensory rod O, arms *s*, affixed thereon, guide-wire P, and the faller-arm N, secured to the suspensory-rod with its free end connected with the 65 actuating-lever, all as and for purposes substantially as set forth.

4. The revoluble spindle, the guide-wire adapted to traverse lengthwise thereof, the rocking suspensory rod and its actuating 70 faller-arm N, and spring 3, combined with the guide-head S, operating screw-rod T, rail C, lever M, means to actuate said lever, the builder-shoes, means to actuate them, shaft W, 75 arms *p* and *s*, pinion *z*, gear *y*, toothed wheel *x*, rack *w*, and bar V, movable endwise and controlled by the said builder-shoes, substantially as stated.

In testimony whereof I affix my signature in presence of two witnesses.

THOMAS J. MURDOCK.
